UNITED STATES PATENT OFFICE.

ROBERT J. CLAY, OF NEW YORK, N. Y.

IMPROVEMENT IN MECHANICAL TOYS.

Specification forming part of Letters Patent No. 131,849, dated October 1, 1872.

To all whom it may concern:

Be it known that I, ROBERT J. CLAY, of the city, county, and State of New York, have invented a new and useful Mechanical Bear-Toy; and I do hereby declare that the following is a full, clear, and exact description of the same, reference being had to the accompanying drawing forming part of this specification, and in which—

Figure 1 represents an outside view of the mechanical bear in an erect position with its covering removed; Fig. 2, a partially vertical section of the same in a crouching position.

My invention consists in certain mechanical movements and combinations of movements applied to an automaton or toy which may be supposed to represent a bear, whereby, on winding up clock-work for setting the parts in motion, the imitation animal, which rests on its haunches, is made to raise and lower itself from a crouching to an erect position and back again, to shake or work its fore paws or limbs, to open and close its mouth, and to turn its head to and fro in a snapping manner, thus giving to the automaton actions which invest it with the semblance of life.

In the accompanying drawing, A represents the main portion or body of the animal; B, its head; C, its hind legs or limbs; and D D, its fore legs. A covering resembling the natural skin or coat of the animal is applied to the exterior of the several parts. The body A is made to contain the clock-work, which may be of any suitable description, and is here represented as consisting of a coiled spring, b, having a winding-arbor, c, projecting through the side of the animal, and provided with a ratchet and pawl, said arbor c giving motion, by means of a wheel, d, to a train of gear, e, f, g, h, i, k, and l. Said body A is pivoted below to rock on a cross-pin, m, on the ends of which the hind limbs C are fitted. Upon the revolving arbor c is a toe, E, that works against a cam, F, fast to one side of the front portion of the body or frame carrying the clock-work, said toe and cam being so shaped that the toe in revolving operates during a part of its rotation upon or against the cam to gradually raise the body from its crouching position, shown in Fig. 2, to the erect posture represented for it in Fig. 1, and afterward, or as the protrud-

ing portion of the toe leaves the cam, and after it has left it, admits of the body falling by its weight onto the heel or hub of the toe, where it remains till again lifted. The fore limbs D D of the animal are vibrated from a cross-joint pin, o, as a center of motion to shake or work as if pawing by cranks on opposite ends of the spindle which carries the gears e f, one, G, of which cranks is shown in Fig. 1. Each of these cranks is connected, by a separate pitman, H, to the limb D it controls, and said cranks should be so set that the up-and-down motion of either limb D is alternate. The lower jaw of the animal is pivoted at n, and is opened and closed in moderately rapid succession by means of a cam, I, on the spindle of the gears e f operating against a toe connected with a lever, q, which is attached, by a cord, r, to the jaw and acts in concert with a spring, s, to produce an opposite action on the jaw to that of the cam. The head B is slightly turned in one direction at intervals, and returned in a sudden or snapping manner to its original or straight position, as follows: The neck portion of said head has attached to it a pivot, t, which connects it with the frame of the body or bracket u therefrom, and provides for the turning of the head. Upon the one side of the main wheel d is a pin, v, which, as it comes round in the rotation of the wheel, temporarily acts upon a cam-like projection of a lever, K, that may have its fulcrum on the cross-pin m, and which, being forced away by the pin v, pulls upon a cord, w, that, running and being suitably guided up through the body and attached to the head at x on one side of the pivot t, causes the head to be gradually turned in one direction. So soon, however, as the pin leaves the cam-like projection of the lever K, a spring, L, arranged to pull on the opposite side of the head to that on which the cord w is attached, operates to suddenly jerk the head back to its normal position, thus, or when combined with the opening and closing of the mouth, giving the animal a snapping action.

What is here claimed, and desired to be secured by Letters Patent, is—

1. The combination of the revolving toe E with the cam F and body A of the animal, ar-

ranged to rock on a lower cross-pin or pivot, *m*, substantially as specified.

2. The combination, with the fore limbs *D*, of the revolving cranks *G* and connecting-
rods *H*, essentially as and for the purpose
herein set forth.

3. The combination, with the head *B*, con-

structed to turn, as described, and fly back, of
the mechanism for opening and closing the
lower jaw, essentially as herein set forth.

ROBT. J. CLAY.
